United States Patent Office

Des. 228,705
Patented Oct. 23, 1973

228,705

PEDESTAL BASE

Stanley E. Thorwaldsen, Grosse Pointe Farms, Mich., assignor to Lear Siegler Incorporated, Detroit, Mich.

Filed Feb. 22, 1972, Ser. No. 228,426

Term of patent 14 years

Int. Cl. D6—06

U.S. Cl. D6—29

Fig. 1

FIG. 1 is a perspective view of a pedestal base showing my new design;

FIG. 2 is an elevational view;

FIG. 3 is a fragmentary cross sectional view taken along line 3—3 of FIG. 2; and

FIG. 4 is a cross sectional view taken along line 4—4 of FIG. 2.

I claim:

The ornamental design for a pedestal base, substantially as shown and described.
